UNITED STATES PATENT OFFICE.

JOHN A. KAYE, OF SAULT STE. MARIE, ONTARIO, CANADA.

COMBINED ENVELOPE AND LETTER SHEET.

Application filed December 10, 1923. Serial No. 679,543.

To all whom it may concern:

Be it known that I, JOHN A. KAYE, a subject of the King of Great Britain, residing at Sault Ste. Marie, in the Province of Ontario, and Dominion of Canada, have invented certain new and useful Improvements in Combined Envelopes and Letter Sheets, of which the following is a specification.

10 The present invention relates to a combined envelope and letter sheet, and has for its object to provide a device of this character which embodies novel features of construction, whereby the letter, after being 15 written, can be readily folded and housed or sealed within an envelope portion which is associated therewith for transmission through the mails.

The envelope and letter sheet are formed 20 from a single sheet of paper, so that an envelope of the proper size is always ready for mailing the letter, and there is no possibility of the letter sheets being placed in the wrong envelopes when several letters are 25 written and prepared for mailing at the same time.

Among the objects of the invention are 30 to provide a combined envelope and letter sheet which is comparatively simple and inexpensive in its construction, which can be readily folded and sealed for transmission through the mails, which can be opened by the recipient without danger of tearing or mutilating the letter and which is so constructed that when the letter sheet is folded 35 the name and address of the person to whom the letter is directed appearing at the top of the letter sheet will be displayed through a window in the front of the envelope, so that the necessity of writing the name and address of the recipient twice, first upon the letter and then upon the envelope, is avoided.

With the foregoing and other objects in 45 view, the invention consists in a peculiarly constructed envelope and letter sheet which will be readily understood from the following description and accompanying drawings, the novel features thereof being 50 pointed out in the appended claims.

In the drawings, Figure 1 is a plan view 55 of a combined envelope and letter sheet embodying the present invention, showing the same in the position assumed before being folded.

Figure 2 is a front view of the envelope

and letter sheet after being folded and when ready for transmission through the mails.

Figure 3 is a rear view thereof.

Figure 4 is a perspective view showing 60 the combined envelope and letter sheet when partially folded.

The combined envelope and letter sheet is adapted to be formed from a single sheet of material and the shape thereof before being folded and sealed for transmission through the mails is shown by Figure 1. The numeral 1 designates the portion of the blank which is adapted to form the front 70 of the envelope. End flaps 2 are provided at the ends of the part 1 and a bottom flap 3 is provided at one side thereof. The opposite side of the portion 1 is connected by a fold line with the head portion 4 of a letter sheet 5. The head portion 4 of the letter sheet is adapted to be folded against the envelope front 1 and corresponds in general with the size and shape thereof, although it may be slightly smaller than the envelope front so that there will be nothing 80 to interfere with the proper folding of the end flaps 2 and bottom flap 3. The body portion 5 of the letter sheet may be of any desired size and shape, and in the present 85 instance is shown as being wider than the head portion 4.

The letter is intended to be written upon the body portion of the letter sheet 5, and either one or both sides thereof may be used for the communication, as desired by the writer of the letter. After the letter has been written the sheet 5 may be folded upon the transverse fold lines 6, and the end portions of the folded letter sheet may then be bent over upon the fold lines 7, so that the 90 folded letter sheet will correspond substantially in size and shape with the envelope front 1 and fit against the same.

The head portion 4 of the letter sheet is 100 folded against the envelope front 1, and the folded body portion of the letter sheet 5 is then folded against the head portion 4. The end flaps 2 may then be bent rearwardly on the fold lines 8 so as to extend over the back portion of the folded letter sheet. The bottom flap 3 is then folded 105 upon the line 9 against the end flaps. The end flaps are of such a length that they meet at substantially the middle portion of the envelope, and the bottom flap has a substantially triangular formation. It extends from the top to the bottom of the envelope.

velope and terminates in a tongue 10 which extends beyond the top of the envelope.

The bottom flap 3 is formed with side portions 3^a which are gummed and a central portion 3^b which is free from gum, the central portion being separated from the gummed portions by the tear lines 11. The gummed portions 3^a overlap and are secured to the underlying end flaps 2, so that the end flaps and bottom flap are secured together and cooperate with each other to form the back of the envelope.

The end flaps 2 are formed with tongues 12 which extend beyond the top of the envelope and are adapted to be folded around the upper edge thereof. The tongue 10 of the bottom flap and the tongues 12 of the end flaps may or may not be gummed, as desired, and are adapted to be folded around the upper edge of the envelope and inserted through slots 13 in the upper portion of the front of the envelope.

The envelope front 1 may be formed with a window or opening 14, and the head portion 4 of the letter sheet has a space 15 defined thereon within which the address of the addressee is adapted to be written, and which is visible through the window when the letter sheet is folded and sealed within the envelope. The usual letter head may be printed upon the head portion 4 of the letter sheet, as indicated at 16, if so desired. By providing the envelope front with the window 14 and arranging the address of the addressee in the space 15, so that it will be displayed through the window when the letter sheet is folded, the necessity of separately addressing the envelope is avoided, thereby saving labor and rendering it certain that the envelope will be correctly addressed when it is prepared for mailing.

A stamp 17 may be applied to the envelope in the usual position, and this stamp partially overlaps one of the tongues 12, as indicated on Figure 2, so that it assists in sealing the envelope and preventing attempts to tamper with the contents thereof. When it is desired to open the envelope, the tongue 10 of the bottom flap is pulled out from the slot 13, or torn away from the envelope, as may be most convenient for enabling the fingers to obtain a grip thereon. The tongue is then forcibly drawn downwardly at the rear of the envelope, thereby separating the central ungummed portion 3^b of the bottom flap 3 from the side portions 3^a thereof which were secured to the end flaps by means of the adhesive which was applied thereto. The tear lines 11 enable the central ungummed strip 3^b of the bottom flap to be readily torn away from the side portions 3^a thereof, and the tear lines may comprise double or triple rows of perforations, so that the tearing of the paper along the desired lines will be ren-

dered certain. Additional tear lines 18 extend along the bottom or lower edge of the envelope from the lower ends of the tear lines 11 to the respective ends of the envelope. After the middle portion 3^b of the bottom flap has been completely severed from the side portions 3^a along the tear lines 11, the lower edge of the envelope can be opened up along the tear lines 18. This enables the end flaps 2 to be swung outwardly, after the tongues 12 thereof have been withdrawn from the slots 13, whereupon the letter sheet can be unfolded and the communication thereon opened up for inspection and reading. If found desirable the tongues 10 and 12, after being folded over the upper edge of the envelope and inserted in the slots 13, may be engaged by small stickers 19 to assist in holding the same in position.

While one particular form of my combined envelope and letter sheet has been illustrated and described in detail, it will be understood that many modifications and changes can be made in the design and details of construction without departing in any manner from the spirit of the invention and the scope of the claims.

If desired an ear 20 may be stamped from the middle tongue 10 and when the envelope is folded and sealed this ear 20 will engage and interlock with a slit 21 in the front of the envelope. This assists in locking the tongue 10 in position and it is, of course, optional whether or not adhesive is used upon the tongues 10 and 12.

Having thus described my invention what I claim as new and desire to secure by Letters Patent of the United States, is—

1. A combined envelope and letter sheet comprising an envelope front having a plurality of slots formed therein adjacent the upper edge thereof, a letter sheet integral with the envelope front and connected to the upper edge thereof, said letter sheet being adapted to be folded against the front, end flaps at the ends of the envelope front which are foldable against the folded letter sheet, and a bottom flap foldable over the end flaps and connected thereto by an adhesive, the bottom flap and end flaps being each formed with a tongue which is foldable around the upper edge of the envelope and insertable through a corresponding one of the slots in the front of the envelope.

2. A combined envelope and letter sheet including an envelope front which is provided with a plurality of slots arranged in substantial alignment with each other, a letter sheet integral with one side of the envelope front and foldable against the said front, end flaps at the ends of the envelope front which are foldable against the letter sheet, and a bottom flap foldable against the end flaps, the end flaps and bottom flap

being each formed with a tongue and the several tongues being adapted to be returned around an edge of the envelope and inserted within the before mentioned slots in the envelope front, the bottom flap having edge portions which are adapted to be secured to the end flaps and the central portion of the bottom flap which terminates in the tongue being separated from the said edge portions thereof by tear lines so that the envelope can be opened by pulling rearwardly upon the tongue of the bottom flap and severing the middle portion thereof from the edge portions thereof along the tear lines.

15 3. A combined envelope and letter sheet including an envelope front having a series of slots formed therein in substantial alignment with each other and adjacent to the upper edge of the front, a letter sheet integral with the envelope front and connected by a fold line to the upper edge of the

front, said letter sheet being adapted to be folded against the front, end flaps provided at the ends of the envelope front and foldable against the folded letter sheet, and a 25 bottom flap foldable over the end flaps, said bottom flap having an adhesive applied to edge portions thereof for engagement with the end flaps and having a middle portion which is separated from the rest of the flap by tear lines and terminates at the free end of the flap in a tongue which can be pulled rearwardly to sever the said middle portion of the flap along the tear lines to open the envelope, the end flaps being each formed 30 with a tongue and the several tongues being foldable around the upper edge of the envelope and insertable through the before mentioned slots.

In testimony whereof I affix my signature.

JOHN ARTHUR KAYE.
